Primary Examiner — Kelley Donnelly(74) *Attorney, Agent, or Firm* — Volk & McElroy, LLP; Michael D. Volk, Jr.(57) **CLAIM**

The ornamental design for a drywall knife and tool holder, as shown and described.

DESCRIPTION

FIG. 1 is a perspective view of a drywall knife and tool holder showing my new design.

FIG. 2 is a top view thereof.

FIG. 3 is a bottom view thereof.

FIG. 4 is a front view thereof, the rear view is the same as the front view.

FIG. 5 is a right side view thereof, the left side view is the mirror image of the right side view.

FIG. 6 is a sectional view through the section 6-6 of FIG. 2. FIG. 7 is a sectional view through the section 7-7 of FIG. 2; and,

FIG. 8 Is a sectional view through the section 8-8 of FIG. 2. The broken lines in the drawings depict features that form no part of the claimed design.
